[57] ABSTRACT

A waveguide band-stop filter utilizes a sequence of capacitive irises to form a plurality of resonant circuits connected in tandem. In the disclosed embodiment the filter is constructed of two sets of plates having iris-defining apertures of different sizes assembled to form a laminated structure with the plates disposed in alternating sequence. The filter is dimensioned larger than the waveguide but is of relatively short length.

STOP BAND FILTER

FIELD OF THE INVENTION

The present invention relates in general to frequency selective apparatus for filtering signals which are in the microwave portion of the electromagnetic frequency spectrum. More particularly, the present invention relates to frequency filters for use with waveguides and of the band-stop type.

BACKGROUND OF THE INVENTION

In many microwave systems the signal frequency is transmitted and guided within the system with a minimum of attenuation, while undesired frequency bands are strongly attenuated by band-stop filters which pass the desired frequencies with low attenuation. One typical band-stop filter comprises a plurality of band-stop resonator cavities which are coupled to the main waveguide by inductive irises. In order to avoid interaction between the fringing fields at the various resonator irises, the resonators are spaced three-quarter guide wavelengths apart. Thus, these prior art band-stop filters have been relatively long and bulky.

Other filters that are used for microwave frequency filtering include corrugated and waffle-iron filters. One filter of this type is shown in U.S. Pat. No. 3,597,710. As indicated in that patent these filters are constructed to fit within the dimensions of a conventional waveguide and because of the dimensional limitations imposed upon the filter they do not have a relatively narrow stop-band width. These types of filters are usually used as low-pass filters.

OBJECTS OF THE INVENTION

One important object of the present invention is to provide an improved band-stop filter for use with a waveguide and that can be constructed relatively compactly.

A further object of the present invention is to provide an improved band-stop filter in accordance with the preceding object and that is relatively short in length in comparison with known band-stop filters.

SUMMARY OF THE INVENTION

As previously indicated, the typical design for a band-stop filter involves commencing with a waveguide structure, providing spaced resonator cavities and coupling the resonator cavities to the waveguide by means of inductive irises, for example. Other filters used as band-pass filters, such as a corrugated filter, are usually constructed within the dimensional limitations of the particular waveguide size employed. However, it has been discovered in this invention that a band-stop filter can be constructed by using alternate iris-defining plates of different aperture size, and by permitting one of the plates to have an iris comparable to the size of the waveguide and the other plate to have an iris larger than the size of the waveguide.

In the disclosed embodiment of the invention the filter comprises a first set of plates having iris-defining apertures of a first rectangular size and a second set of plates having iris-defining apertures of a second rectangular size larger than the first size. Means are provided for assembling the plates together to form a laminated structure with the first plates disposed alternately with respect to the second plates. In accordance with the in-

vention, the first plates are constructed having an aperture size that is comparable to the dimensions of the waveguide. The second plates are constructed having an aperture size that is larger than the waveguide dimensions. Regarding the second plates the aperture in one dimension may be approximately twice the dimension of the waveguide. Finally, means are provided for coupling the filter to opposite waveguide sections.

BRIEF DESCRIPTION OF THE DRAWINGS

Numerous other objects, features and advantages of the invention will now become apparent upon the reading of the following detailed description taken in conjunction with the accompanying drawings in which:

FIG. 1 is a perspective view of a microwave band-stop filter according to one embodiment of the present invention;

FIG. 2 is a vertical section taken along the longitudinal axis of the filter of FIG. 1, when the filter is inserted in a waveguide structure;

FIG. 3 shows in detail the formation of resonant circuit within the filter;

FIG. 4 represents the equivalent circuit of the resonant circuit of FIG. 3;

FIG. 5 is a front elevation of a modification of the filter shown in FIGS. 1 and 2; and

FIG. 6 is a longitudinal sectional view similar to that shown in FIG. 2 and modified for stopping both the second and third harmonics.

DETAILED DESCRIPTION

Referring now to the drawings, and in particular to FIGS. 1-3, there is shown a microwave filter 10 which is for connection to a rectangular waveguide section. For a signal propagated through the waveguide structure, the filter causes a desired level of attenuation of components of the signal in a selected one of the harmonic bands in relation to the main pass-band of the waveguide structure.

The filter 10 is constructed from nineteen rectangular plates, each plate having a uniform predetermined thickness t and each plate also having the same external dimensions. The plates comprise nine first iris-defining plates 11 interleaved with eight second iris-defining plates 12, and two end plates 13. Rectangular shaped apertures, the boundaries of which are indicated at 14, 15 and 16, are stamped out of the plates 11, 12, and 13, respectively, and the plates are then coated with a metal having a low loss factor. The plates are secured together in any convenient manner to form a laminated construction, and the external surfaces of the assembled filter 10 are hermetically sealed by being coated with solder. The filter is secured in the main guide 18 of the waveguide structure as shown in FIG. 2.

The rectangular main guide 18 has a width a and a height b , and the apertures 14, 15 and 16 in the plates 11, 12 and 13 of the filter are each of a width a . The height of the aperture 16 in each end plate 13 is m , as indicated in FIG. 2. As indicated in FIG. 3, the height of the aperture 14 in each first iris-defining plate 11 is c , and the height of the aperture 15 in each second iris-defining plate 12 is l . In FIG. $3c + 2p = 1$. The centres of the apertures 14, 15 and 16 are co-incident with the centres of the plates 11, 12 and 13 in which the apertures are formed. Thus, the passage through the filter 10 has different sectional areas, the longi-

3
tudinal axis of the filter being coincident with the longitudinal axis of the main guide 18.

As is more clearly shown in FIG. 3, each adjacent pair of first iris-defining plates 11 and the second iris-defining plate 12 between them together form a resonant circuit indicated generally at 19 between the broken lines 20. The filter has eight such resonant circuits 19 in tandem with each other. Each resonant circuit reflects components of signals within the stop band associated with the filter, the resonant frequency of each circuit being the centre frequency of the stop band. The centre frequency is predetermined to be such that the stop band comprises the selected harmonic band required to be attenuated by the filter. The greater the number of resonant circuits within the filter the greater the level of attenuation of components of the signal within the selected harmonic band.

Each end plate 13 and the first iris-defining plate 11 with which it is contiguous comprise a transformer circuit between the main guide 18 and the series of resonant circuits 19 of the filter 10. The height m of the aperture 16 in each end plate is arranged to be the mean value of the height b of the section of the main guide 18 and the height c of the aperture 14 in each first irisdefining plate 11. Thus, each transformer circuit has an admittance value equal to the mean of the admittance value of the main guide and the admittance value of each resonant circuit 19. The shunt capacity of the discontinuity between the main guide 18 and the adjacent resonant circuit 19 may be ignored.

The heights of the apertures in the plates can be expressed by the following equation: for the end plates 13;

$$m = \frac{b}{2} [1 + (1 + K^2)^{1/2} - K],$$

for the first iris-defining plates 11;

$$c = b [1 + (1 + K^2)^{1/2} - K],$$

and for the second iris-defining plate 12;

$$1 = b [1 + (1 + K^2)^{1/2} - K] + 2p.$$

Because K is positive $c < m < b$ The way in which the value of K is derived is indicated below.

Also below it is shown that, if L_s is the desired level of attenuation by the filter 10 of the components of the signal in the selected harmonic band, then the number (n) of resonant circuits 19 required in the filter to cause, at least, the desired level of attenuation is given by the equation:

$$n > \frac{L_s + 10}{20 \log [P_o + (P_o^2 - 1)^{1/2}]}$$

where $P_o = 1 - 4t^2 Y/bp$ ($\lambda g/\lambda go - 1$), Y is the characteristic admittance of a length of the filter, and (λg) and (λgo) are respectively, the wavelength in the guide at any frequency and at the center frequency of the stop band.

In one particular embodiment of the stop band filter for a waveguide structure having a main passband of 5.9 to 6.4 GigaHertz, which corresponds to a conventional rectangular waveguide identified as a WR 137 having dimensions 1.37 inches by .622 inches, the filter causes attenuation of components of a signal in a selected one of the 11.8 to 12.8 GigaHertz or 17.7 to 19.2 GigaHertz etc. harmonic bands. Each plate of the filter has the same thickness, in the range 0.03 inch to 0.1 inch, determined by the convenience of manufacturing the plates. The external dimensions of the plates are larger than the sectional dimensions of the main guide.

5
The theory underlying the design of a microwave stop band filter according to the present invention will now be given.

In the dominant H_{01} mode for the filter, with plates having rectangular shaped apertures, the equivalent circuit of the resonant circuit 19 shown in FIG. 3 is represented by the circuit diagram shown in FIG. 4. The equivalent circuit comprises reactance (jX) between two identical impedances Z , where Z is the characteristic impedance of a length of the filter with respect to the main guide 18. This impedance Z is defined by the transfer matrix:

$$\begin{bmatrix} \cos 2\theta_1 jZ \sin 2\theta_1 \\ jY \sin 2\theta_1 \cos 2\theta_1 \end{bmatrix} \quad (1)$$

where ($Y = 1/Z$) and ($\theta_1 = \beta t/2$), β being the signal wave velocity within the filter 10.

The reactance X is given by the equation:

$$20 \quad X = 2Z_s \tan \theta_2 \quad (2).$$

where $\theta_2 = \beta p$ and $Z_s = t/b << 1$.

The transfer matrix of the resonant circuit is therefore:

$$25 \quad \begin{bmatrix} \cos 2\theta_1 jZ \sin 2\theta_1 \\ jY \sin 2\theta_1 \cos 2\theta_1 \end{bmatrix} \begin{bmatrix} 1 & j2Z_s \tan \theta_2 \\ 0 & 1 \end{bmatrix} \begin{bmatrix} \cos 2\theta_1 jZ \sin 2\theta_1 \\ jY \sin 2\theta_1 \cos 2\theta_1 \end{bmatrix} \\ 30 \quad \begin{bmatrix} \cos 4\theta_1 - Z_s Y \tan \theta_2 \sin 4\theta_1 \\ jY (\sin 4\theta_1 - 2Z_s Y \tan \theta_2 \sin^2 2\theta_1) \end{bmatrix} \begin{bmatrix} j(Z \sin 4\theta_1 + 2Z_s \tan \theta_2 \cos^2 2\theta_1) \\ \cos 2\theta_1 - Z_s Y \tan \theta_2 \sin 4\theta_1 \end{bmatrix} \quad (3)$$

35
This may be written as:

$$\begin{bmatrix} \cos \psi jZ_1 \sin \psi \\ jY_1 \sin \psi \cos \psi \end{bmatrix} \quad (4)$$

40
where $\psi = \cos^{-1} (\cos 4\theta_1 - Z_s Y \tan \theta_2 \sin 4\theta_1)$

$$Z_1 = Z \left(\frac{\sin 4\theta_1 + 2Z_s Y \tan \theta_2 \cos^2 2\theta_1}{\sin 4\theta_1 - 2Z_s Y \tan \theta_2 \sin^2 2\theta_1} \right)^{1/2} \quad (5)$$

or

$$45 \quad Z_1 = Z \left(\frac{1 + Z_s Y \tan \theta_2 \cot 2\theta_1}{1 - Z_s Y \tan \theta_2 \tan 2\theta_1} \right)^{1/2} \quad (6)$$

In the main passband θ_1 and θ_2 are small, so equation (6) becomes:

$$50 \quad Z_1 = Z (1 + Z_s Y A \theta_2/\theta_1)^{1/2} = Z \left(\frac{Ap}{Zb} \right)^{1/2} \quad (7)$$

where the error factor $A = \tan \beta p / \beta p$

In relation to the 5.9 to 6.4 GigaHertz passband of the waveguide structure:

p is selected to be a quarter wavelength at the center frequency of the desired stop band.

For stop bands far removed from the passband A is approximately 1.0.

60
If the resonant circuit is matched with the main guide:

$$Z_1 = 1$$

Hence, from equation (7):

$$Z^2 + 2KZ - 1 = 0,$$

$$65 \quad \text{or} \quad Z = \frac{1}{2} \left(1 + K^2 \right)^{1/2} - K \quad (8)$$

where

$$K = pA/2b$$

90
since Z must be less than unity.

If within the filter there are cascaded a plurality (n) of identical resonant circuits, each resonant circuit is described by the transfer matrix of equation (4), (the condition represented by equation (8) being considered to be obeyed). Thus, each resonant circuit, and the whole filter, is matched to the main passband of the waveguide structure. The overall transfer matrix of the filter is:

$$\begin{bmatrix} \cos n\psi jZ_1 \sin n\psi \\ jY_1 \sin n\psi \cos n\psi \end{bmatrix} \quad (10)$$

The insertion loss L associated with the filter is given by the equation:

$$L = 10 \log [1 + (Z_1 - Y_1)^2/4 \sin^2 n\psi] \quad (11)$$

In the selected stop band each series resonant circuit is arranged, at least, to be near to resonance, and therefore:

$$\tan \theta_2 \Big|_{\theta_2 \approx \frac{\pi}{2}} \approx \frac{1}{\frac{\pi}{2} \left(\left| -\frac{\lambda g_0}{\lambda g} \right| \right)} \quad (12)$$

where λg is the guide wavelength, and λg_0 is the guide wavelength at the resonant frequency of each resonant circuit. Since θ_2 is small equation (5) becomes:

$$\psi \approx \cos^{-1} [1 - 4t^2 Y/bp (\lambda g/\lambda g_0 - 1)] \quad (13)$$

and equation (6) becomes

$$\begin{aligned} Z_1 &\approx jZ \cot 2\theta, \\ &\approx j2Z p/t \pi \cdot \lambda g/\lambda g_0 \end{aligned} \quad (14)$$

Substituting equations (13) and (14) in equation (11):

$$L = 10 \log [1 - (Z_1 - Y_1)^2/4 \sinh^2 (n \cosh^{-1} P)],$$

with

$$P = 1 - t^2 Y/bp (\lambda g/\lambda g_0 - 1)$$

Since $p > 1$:

$$\begin{aligned} L &\approx 10 \log \left[-\frac{(Z_1 - Y_1)^2}{16} [P + (P^2 - 1)^{1/2}]^2 \right] \\ &= 20n \log [P + (P^2 - 1)^{1/2}] + 20 \log \left[+j \frac{(Z_1 - Y_1)}{4} \right] \end{aligned} \quad (15)$$

From equation (14), because p is always less than b and because Z is approximately equal to 1.0, the contribution of the second term of equation (15) is -10db or less. Thus:

$$(L + 10) > 20n \log [P + (P^2 - 1)^{1/2}] \quad (16)$$

If the guide wavelengths at the lower and upper frequencies (f_1) and (f_2) of the selected harmonic band are, respectively, λg_1 and λg_2 then: $\lambda g_0 \approx (\lambda g_1 + \lambda g_2)/2$ Therefore, if L_s is the desired level of attenuation for components of the signal in the selected harmonic band:

$$n > \frac{L_s + 10}{20} \cdot \frac{1}{\log [P_0 + (P_0^2 - 1)^{1/2}]} \quad (17)$$

$$\text{with } P_0 = 1 - 4t^2 Y/bp (\lambda g/\lambda g_0 - 1) \quad (18)$$

For example, assume the following dimensions:

$$t = .05, b/Y = 0.5 \text{ and } p = .31$$

$$P_0 = 1 - 4 \cdot .05 \cdot .05 \cdot .5 \cdot .31 (\lambda g - 1)/\lambda g_0 = 1 + .064/(\lambda g/\lambda g_0 - 1)$$

Hence, the stop bandwidth is approximately ± 6.4 percent. Note that the bandwidth is a function of the thickness of the plates and the p dimension. For providing a stop band that is relatively narrow, attenuating only undesired frequencies, the thickness should be relatively small and the dimension p is large compared with waffle iron or corrugated filters thereby requiring that the filter have dimensions larger than the guide 18.

FIG. 5 shows a modified version of the waveguide that may be preferred in attenuating higher order modes. In this embodiment there is provided slots 21 in the first iris-defining plates 11. The slots 21 are in each

first iris-defining plate 11 and are arranged in rows which extend parallel to the longitudinal axis of the filter. The depth of the slots 21 are such that the slots do not extend beyond the projection of the aperture 16 in each end plate 13 onto the plates 11.

It is possible to have a filter with a plurality of constituent plates such that the value of p is not constant throughout the filter, the design procedure being modified accordingly. The first iris-defining plate 11 between adjacent resonant circuits having different values for p , and therefore different characteristic impedances Z , preferably should be stepped so as to have two apertures each of a thickness ($t/2$). The different heights of the apertures are arranged to be such that the required different admittances for the adjacent resonant circuits are provided. However, the first iris-defining plate 11 between the resonant circuits may have a single aperture of a constant height throughout its thickness, the height of the aperture being such that there is obtained a mean admittance value of the two desired admittance values for the adjacent resonant circuits.

Another embodiment of the invention is shown in FIG. 6. This embodiment is used for suppressing two stop bands.

The structure of FIG. 6 is quite similar to that shown in FIG. 2 except for the addition of middle section 25. The end sections 26 may be identical in design to the plates shown in FIG. 2. In FIG. 6 the dimension c is comparable to guide dimension b and the dimension d is approximately equal to one-fourth b .

In order to attenuate the level of components of the signal in more than one stopband it is also possible to combine a plurality of filters of the type shown in FIG. 2, different constituent filters causing the attenuation of components of the signal in the different harmonic bands. The input and output transformer circuits of adjacent filters of such a combination comprises a single circuit having a characteristic admittance value equal to the mean of the desired admittance values of the input and output transformer circuits of the adjacent filters.

A filter according to the present invention, capable of attenuating components of a signal in a selected stopband to the main passband, is particularly advantageous when, as is usual, the passband is defined by a bandpass waveguide filter also having a response at higher frequencies to the main passband frequencies.

A filter according to the present invention may be employed in a waveguide structure in a communication system. In such a system it is necessary to attenuate only components of a signal which comprise harmonics to the communication band, the communication band comprising the main passband of the waveguide structure. If components of the signal in more than one harmonic band are required to be attenuated a combination of filters is employed. In such a case, conveniently, the constituent filters cause different levels of attenuation for components in the different selected harmonic bands. Since components of the signal which are neither in the communication band nor in a selected harmonic band are not required to be attenuated, each filter is simple in construction and small in size. The filter of this invention is particularly useful when it is desired to reject only the second harmonic.

The filter described above, with plates having rectangular shaped apertures, is for use with a main guide having a rectangular shaped section. However, it is possible to construct a filter with plates having apertures

of any convenient shape, and for use with a main guide having an appropriately shaped section.

A stop band filter according to the present invention may cause attenuation of components of a signal other than components solely in a selected harmonic band in relation to the main passband. The resonant circuits of the filter are arranged to resonate at the predetermined centre frequency of the required stop band.

A filter according to the present invention, and capable of attenuating components of a signal in a predetermined stop band may not necessarily be formed with a laminated construction from an assembly of apertured plates, but may be constructed in any convenient manner.

The laminated construction, if employed, is simple 15 and the design procedure to be adopted in order to obtain a filter having a required specification is simpler than with known forms of stop band filter.

A filter according to the present invention can operate successfully with microwave signals of higher power 20 than those required to be propagated in a communication system. The filter also has a lower insertion loss factor in relation to the main passband than for some previously known constructions of such filters.

Having described a limited number of embodiments 25 of this invention, one skilled in the art should readily recognize that other structures will fall within the spirit and scope of the present invention which is to be lim-

ited solely by the appended claims.

What is claimed is:

1. A narrow band band-stop filter for use with a waveguide having dimensions a and b and comprising: 5 a first set of relatively thin plates respectively defining a first set of iris-defining apertures having an aperture dimension c , a second set of relatively thin plates respectively defining a second set of iris-defining apertures having an aperture dimension 1 , said aperture dimension 1 being larger than said aperture dimension c and larger than the waveguide dimension b , said first and second sets of plates all being of approximately the same individual thickness t and being disposed in alternating sequence forming corrugations; an aperture difference dimension p being defined as:

$$p = 1 - c/2$$

wherein the stop bandwidth is a function of the ratio:

$$4t^2/bp$$

and the ratio t^2/p is caused to be made small by constructing the plates on the order of 0.1 inches thick or smaller and making the p dimension on the order of a quarter wavelength at the center frequency of the stop band,

and means coupling the filter to separate waveguide sections.
